UNITED STATES PATENT OFFICE.

CRAWFORD P. MCGINNIS, OF CHICAGO, ILLINOIS, ASSIGNOR TO THE PYLE-NATIONAL COMPANY, OF CHICAGO, ILLINOIS, A CORPORATION OF NEW JERSEY.

LOCOMOTIVE-HEADLIGHT-FOCUSING ATTACHMENT AND PILOT LIGHT THEREFOR.

Application filed January 7, 1926. Serial No. 79,732.

My invention relates to improvements in locomotive headlight focusing attachment and pilot light therefor and has for one object to provide a new and improved type of headlight wherein all manipulation of the light source for focusing takes place in front of the forward boundary of the reflector and wherein all parts which support or are used to adjust or manipulate or focus it are located in front of the reflector. Another object is to provide an arrangement whereby the light source for major illumination and the pilot light are mounted in the same support. Other objects will appear from time to time throughout the specification and claims.

My invention is illustrated more or less diagrammatically in the accompanying drawings, wherein—

20 Figure 1 is a longitudinal section on a vertical plane through a headlight embodying my invention;

Figure 2 is a section on an enlarged scale through the focusing device;

25 Figure 3 is a section along the line 3—3 of Figure 2.

Like parts are indicated by like characters throughout the specification and drawings.

30 1 is the supporting frame, 2 the housing mounted on the frame by means of a lug 3 and other lugs not here shown. 4 is the reflector bowl engaging a cushion 5 in the housing. The housing is expanded at 6 to contain a reflector holding ring 7 and a 35 supporting collar 8. Projecting radially inward from the supporting collar 8 are the strip arms 9 and a hollow arm 10.

Carried by the arms 9 and 10 is a fixed sleeve 11. In this sleeve is slidably mounted 40 a threaded adjusting sleeve 12 slotted at 13 to engage a pin 14 in the sleeve 11 which pin holds the two sleeves against relative rotation while permitting longitudinal movement. 15, 16 are adjusting nuts threaded 45 on the sleeve 12 engaging or abutting against the sleeve 11. By manipulation of these nuts the adjusting sleeve may be moved longitudinally within the fixed sleeve. 17 and 18 are electric light sockets contained in the 50 ends of the sleeve 12. They carry electric light bulbs, 19 which provides the illumination for the headlight beam and 20 which provides the pilot light. Conductors 21 lead from the sockets 17 and 18 through the 55 sleeves and through an aperture 22 in the

sleeves down through the hollow arm 10 into the housing 1.

The reflector is cut away at 23 in line with the adjusting sleeves 11 and 12 and their associated parts. The sleeves, light 60 sockets and the like are all located on the axis of the reflector.

The position of the bases or sockets in the adjusting sleeve is, of course, fixed. The headlight bulb and the pilot light bulb bear 65 a fixed relation, being located as they are in the adjusting sleeve. Adjustment of the light beam is made by loosening one of the nuts and tightening the other to move the adjusting sleeve longitudinally in the fixed 70 sleeve along the axis of the reflector. No other focusing arrangement is needed because the electric light bulbs can be obtained with the light source properly centered on the axis of the socket so that if the socket is centered on the axis of the reflector it is necessary only to move the light source back and forth along the reflector to directly focus. The light rays from the source impinge on the reflector in the usual way and reflect out in a parallel ray beam. No light 75 is reflected from the blank spot on the reflector, that is, the spot where the reflector is cut away because if the reflector were not cut away and light was reflected it would merely be interrupted by the electric light 80 sockets and associated parts.

85 It will be evident that while I have shown in my drawings an operative device, still many changes might be made in the size, shape, arrangement and disposition of parts without departing materially from the spirit of my invention and I wish, therefore, that my showing be taken as in a sense diagrammatic.

90 The use and operation of this invention are as follows. The light source is suspended in front of the reflector bowl. There is nothing between the light source and the reflector surfaces. Thus the light rays from the light source impinge upon the entire reflector area and since the reflector is most efficient towards its apex, the usual masking of the light toward the apex of the reflector which normally cuts down greatly the efficiency of the reflector is done away with. The masking effect of the members which 100 hold and permit the adjustment of the position of the light source is reduced to a minimum because they are not in line with the 105 110

hole at the apex of the reflector which hole must usually be left there as the result of the requirements of manufacture.

The light source is moved toward and 5 from the reflector along the focal axis by means of a sliding sleeve in which the bulb is mounted, which sleeve slides in a fixed sleeve and is moved backward and forward by means of opposed, threaded collars 10 engaging threads on the sliding sleeve and abutting against the ends of the fixed sleeve. The fixed sleeve is held with its axis in line with the axis of the reflector and the only 15 adjustment in focus possible or necessary is an adjustment back and forth toward the apex of the reflector in line with the axis.

I claim:

1. In a headlight, a reflector bowl, a light 20 support comprising a rigid arm extending across the open mouth of the bowl, a fixed sleeve supported on the arm having its axis coinciding with the axis of the reflector, a floating sleeve slidable therein, longitudinally slotted in its central position and 25 threaded at each end, a pin in the fixed sleeve engaging the slot, nuts on each end of the floating sleeve and abutting against each end of the fixed sleeve, electric lamp sockets in each end of the floating sleeve and lights

socketed therein, located on the axis of the 30 reflector and one projecting toward the other away from the bowl.

2. In a headlight, a reflector bowl, a light support comprising a rigid arm extending across the open mouth of the bowl, a fixed sleeve supported on the arm having its axis coinciding with the axis of the reflector, a floating sleeve slidable therein, longitudinally slotted in its central position and 35 threaded at each end, a pin in the fixed sleeve engaging the slot, nuts on each end of the floating sleeve and abutting against each end of the fixed sleeve, electric lamp sockets in each end of the fixed sleeve, electric lamp 40 sockets in each end of the floating sleeve and lights socketed therein, located on the axis of the reflector and one projecting toward the other away from the bowl, the support being 45 hollow, apertures in both sleeves in register with each other and the hollow support and 50 electric conductors extending radially through the support and the apertures into the interior of the sleeve to the light sockets.

Signed at New York, county of New York and State of New York, this 21st day of 55 December, 1925.

CRAWFORD P. McGINNIS.
